UNITED STATES PATENT OFFICE

146,168

DESIGN FOR A TEETER-TOTTER

Paul Buczkowski, Detroit, Mich.

Application February 15, 1946, Serial No. 126,574

Term of patent 7 years

(Cl. D34—5)

To all whom it may concern:

Be it known that I, Paul Buczkowski, a citizen of the United States, residing at Detroit, in the county of Wayne and State of Michigan, have invented a new, original, and ornamental Design for a Teeter-Totter, of which the following is a specification, reference being had to the accompanying drawing, forming a part thereof, in which:

Fig. 1 is a side elevational view of a teeter totter embodying the invention having certain portions broken away to better illustrate the same;

Fig. 2 is a plan view; and

Fig. 3 is an end elevational view.

I claim:

The ornamental design for a teeter-totter, substantially as shown.

PAUL BUCZKOWSKI.
